(57) **CLAIM**

The ornamental design for a computer memory device, as shown and described.

DESCRIPTION

FIG. 1 is a side perspective view of a computer memory device of the present invention;

FIG. 2 is a front view of the computer memory device of FIG. 1, the rear view is a mirror image;

FIG. 3 is a side view of the computer memory device of FIG. 1, the opposite side is a mirror image;

FIG. 4 is a top view of the computer memory device of FIG. 1; and,

FIG. 5 is a bottom view of the computer memory device of FIG. 1.

The broken line drawing in FIGS. 1-4 is for illustrative purposes only and forms no part of the claimed design.
